UNITED STATES PATENT OFFICE.

CHARLES F. COLEMAN AND HENRY A. SMITH, OF ATLANTA, GEORGIA.

CUT-OUT FOR ELECTRIC LAMPS.

SPECIFICATION forming part of Letters Patent No. 269,013, dated December 12, 1882.

Application filed October 5, 1882. (No model.)

To all whom it may concern:

Be it known that we, CHARLES F. COLEMAN and HENRY A. SMITH, both of Atlanta, in the county of Fulton and State of Georgia, have 5 invented a new and Improved Cut-Out for Electric Lamps, of which the following is a full, clear, and exact description.

Our invention consists in an improved cut-out for systems of electric lighting employing 10 either arc or incandescent lamps.

The object of the invention is to avoid the liability of warping and the burning of the cut-out and connecting wires, which is a great objection to cut-outs as heretofore made. In our 15 improved device we cut out the lamps without breaking the circuit, so that the current has a continuous unbroken connection without the aid of springs or switches to convey the current, as set forth more particularly hereinafter.

Reference is to be had to the accompanying drawings, forming part of this specification, in which similar letters of reference indicate corresponding parts in all the figures.

Figure 1 is a plan view of our improved cut-out. Fig. 2 is a plan view with certain parts removed. Fig. 3 is a section on line xx , Fig. 1. Fig. 4 is an inverted plan view of the turning-block by which the current is shifted.

In the drawings, the cut-out is shown as applied to a suitable base, which may be attached upon the outside of a building or in any other convenient situation; but it is to be understood that the cut-out may be made a part of the inclosing box or case of the lamp, thus 35 reducing the cost of construction.

Referring to the drawings, A is the base, of wood or other suitable material, and upon this are secured metal bars or strips B, which are placed radiating from the center of the base, 40 and upon the outer end of these bars B are binding-posts a . The inner ends of the bars B, at the center of the base, are not in connection with each other, but are separated a suitable distance apart.

Upon a pivot-post, C, at the center of the base A, is a block, D, of wood or other suitable non-conducting material, the bottom of which is enlarged in the form of a square plate of a size for extending over the ends of the 50 metallic bars B. To the under side of the

said block D are fixed two metallic plates, E, parallel with each other and in position for connecting the ends of the bars B.

Upon the circular portion of the block D is a coil-spring, F, one end of which connects with the block, while the other end is connected to a fixed piece or stud, d , on the base A. On the outer end of post C, beneath a head or nut, i , thereon, is a spring, H, which bears on block D, to press the same down with the force required to insure contact. The pressure is adjustable by means of nut i . The block is loose upon the pivot-pin C, so that it can be turned, and it is provided at one side with a projecting pin, b , which is used in connection with a catch, e , on the base, for holding the block in its normal position, in which position the spring F is brought under tension, so that when the catch e is raised the block will be thrown around a quarter-revolution until arrested by 70 the pin b taking against the fixed piece d .

The line-wires are to be connected to two of the binding-posts a , as shown at $m m$, while the circuit-wires n to the lamp are to be connected to the other two binding-posts. In the 75 position of the block D, as shown in Fig. 1, the two metallic plates E connect the metal bars B in such a manner that the incoming current, as shown by the arrows, is carried across by one plate E to one of the bars B in the lamp-circuit, and from thence passes to the lamp represented at H to the other bar B in the lamp-circuit, and thence by the other plate E to the bar B, that is connected with the outgoing line-wire. When it is desired to cut out 85 the lamp the catch e is to be pressed down, and the block D, being thus released, is turned a quarter-revolution by the spring F, so that the plates E connect the two bars B B, to which the line-wires are connected, thus cutting out 90 the lamp without breaking the main circuit.

It will be seen that there are no parts liable to become warped, and there being no period of time in which the circuit is broken, and, further, the conducting-surfaces being ample for 95 the current, there can be no spark or any liability of the parts becoming burned.

The turning-block may be provided with a handle for use in turning the same to its normal position.

Having thus described our invention, what we claim as new, and desire to secure by Letters Patent, is—

The combination, with the base A, having 5 fixed piece d and catch e, of the bars B, radiating from its center, carrying the posts a, and unconnected at their inner ends, the central pivot-post, C, the spring-pressed non-conducting block D, arranged loosely on said post, carrying pin b and extending over the inner ends 10 of said bars, the parallel plates E, made fast

to the under side of said block, and the spring F, connected at one end with stud d and at the other with block D, whereby in the cut-out the circuit is rendered continuous without the aid 15 of springs or switches, as described.

CHARLES F. COLEMAN.
HENRY A. SMITH.
